UNITED STATES PATENT OFFICE.

THOMAS J. HARTMAN, OF CHICAGO, ILLINOIS.

SHOULDER PAD.

Application filed March 12, 1923. Serial No. 624,523.

To all whom it may concern:

Be it known that I, THOMAS J. HARTMAN, a citizen of the United States, and a resident of the city of Chicago, county of Cook, and 5 State of Illinois, have invented certain new and useful Improvements in Shoulder Pads, of which the following is a specification.

My invention relates to improvements in shoulder pads especially adapted for use by 10 foot-ball players and the like, and has for its object the provision of an improved construction of this character especially adapted and arranged for the protection of the arm sockets of joints of the wearer and affording perfect 15 freedom of movement of the arms, the present invention being an improvement on that disclosed in my prior Patent No. 1,310,477 granted July 22, 1919.

Other objects will appear hereinafter. 20 The invention consists in the combinations and arrangements of parts hereinafter described and claimed.

The invention will be best understood by reference to the accompanying drawings 25 forming a part of this specification, and in which,

Fig. 1, is a front view of a shoulder pad embodying the present invention;

Fig. 2, is an enlarged top plan view of one 30 side thereof;

Fig. 3, is a view similar to Fig. 2, but showing the gap guard swung upwardly, and

Fig. 4, is a section taken on line 4—4 of Fig. 2.

The preferred form of construction as illustrated in the drawings, comprises two lower felt strips 5 adapted to pass over the shoulders of the wearer and each carrying on its top a strip of hard leather 6 stitched 35 thereto. The leather strips 6 are laced together by means of lacing 7 at the front and rear and suitable straps provided for securing the pad about the body of the wearer whereby a sort of upper jacket or large collar is provided. A shoulder joint cap, substantially in shallow cup form and consisting 40 of an upper hard leather piece 8 and a lower felt piece 10 stitched together as shown and connected by flexible straps 9 with the

corresponding edges of the shoulder strap 6, one of the shoulder joint caps being provided at each side as shown. Each shoulder joint cap is provided with a strap 11 adapted 45 to pass under the arm of the wearer to hold the same in place and the inner edge 12 of each cap is made outwardly curved in

form as shown. A gap guard 13 consisting of a strip of hard leather is arranged to cover the gap thus formed between the shoulder guard and the joint guard, said gap guard 60 being connected by a piece of flexible webbing 14 with the corresponding leather guard 6 at a point located some distance back from the edge as shown.

By this arrangement a shoulder pad is provided which will afford adequate protection and at the same time permit of the greatest possible freedom of movement. The inner edges 12 of the joint caps are made outwardly curved in form so as to permit of free upward swinging thereof as indicated in dotted lines in Fig. 4. It will be noted that each leather strip 6 is necessarily upwardly curved to pass over the shoulder and this outward concavity of the inner edges of the shoulder 75 caps permits of such upward swinging without contact with the corresponding leather guard 6. This flexibility permits the wearer to extend his arms freely upwardly. The gap guard 13 covers the gap between the 80 shoulder cap and the main guard and thus protects the underlying parts.

While I have illustrated and described the preferred form of construction for carrying my invention into effect, this is capable of 85 variation and modification without departing from the spirit of the invention. I, therefore, do not wish to be limited to the precise details of construction set forth, but desire to avail myself of such variations and 90 modifications as come within the scope of the appended claims.

Having described my invention what I claim as new and desire to secure by Letters Patent is:

1. The combination with a guard curved to fit on top of the shoulder, of a shoulder joint cap flexibly connected with said guard, the inner edge of said cap being outwardly curved in form to form a recess fitting over 100 the shoulder guard when swung upwardly, substantially as described.

2. The combination with a guard curved to fit on the top of the shoulder, of a shoulder joint cap flexibly connected with said guard, the inner edge of said cap being outwardly curved in form to form a recess fitting over the shoulder guard when swung upwardly; and a flexibly mounted guard member overlying the gap between the shoulder guard and cap, substantially as described.

3. A shoulder pad comprising a guard adapted to rest on top of the shoulder, said guard consisting of a lower felt portion and an upper hard leather portion; a shoulder 5 joint cap substantially in cup form and consisting of a lower felt portion and an upper hard leather portion, the inner edge of said cap being outwardly curved in form; and a flexible strap connection between said cap 10 and said guard, substantially as described.

4. A shoulder pad comprising a guard adapted to rest on top of the shoulder, said guard consisting of a lower felt portion and an upper hard leather portion; a shoulder 15 joint cap substantially in cup form and consisting of a lower felt portion and an upper hard leather portion, the inner edge of said cap being outwardly curved in form; a flexible strap connection between said cap and 20 said guard; a cap guard member consisting of a strip of hard leather overlying the gap between said first mentioned guard and said cap; and a flexible strap connection between said cap guard member and said first mentioned guard member and attached to said 25 second guard member at a distance from the outer edge thereof, substantially as described.

5. The combination with a shoulder guard 30 member adapted to rest on top of the shoulder, of a joint cap member flexibly connected with said guard member; a gap guard overlying the gap between said cap and

shoulder guard members and composed of relatively stiff and hard material; and a 35 flexible strap mounting for said gap guard of relatively soft and flexible material, said strap having one end secured to said gap guard and the other end secured to one of said members at a point located well back 40 from the gap between the shoulder guard and the cap members, substantially as described.

6. The combination with a guard member adapted to rest upon the top of a shoulder, 45 of a shoulder joint cap member flexibly connected to said guard by means of a flexible strap, said shoulder guard and cap being made of a relatively stiff and hard material, and said strap of relatively soft and flexible 50 material; a gap guard overlying the gap between said cap and shoulder guard and composed of relatively stiff and hard material; and a flexible strap mounting for said gap guard, said flexible strap being of comparatively soft and flexible material and attached to said shoulder guard at a distance 55 from the gap between it and said cap, substantially as described.

In testimony whereof I have signed my 60 name to this specification in the presence of two subscribing witnesses.

THOMAS J. HARTMAN.
